US0D1102048S

(12) **United States Design Patent** (10) **Patent No.:** **US D1,102,048 S**
Yildirim (45) **Date of Patent:** **** Nov. 11, 2025**

(54) **SEPARATOR FOR BEEHIVE**

(71) Applicant: **YILDIRIM PLASTIK MAKINE KALIP SAN. TIC. LTD.STI**, Istanbul (TR)

(72) Inventor: **Muzaffer Yildirim**, Istanbul (TR)

(**) Term: **15 Years**

(21) Appl. No.: **35/522,024**

(22) Filed: **Jul. 1, 2024**

(80) **Hague Agreement Data**

Int. Filing Date: **Jul. 1, 2024**

Int. Reg. No.: **DM/239284**

Int. Reg. Date: **Jul. 1, 2024**

Int. Reg. Pub. Date: **Aug. 23, 2024**

(51) **LOC (15) Cl.** **30-02**

(52) **U.S. Cl.**

USPC **D30/119**; D30/120

(58) **Field of Classification Search**

USPC D30/108, 110, 114, 116, 117, 118, 119, D30/120, 160, 199

CPC A01K 47/00; A01K 47/02; A01K 47/06; A01K 49/00
